LIGHTNING ARRESTER

Austin J. Fink, Pittsburgh, Pa., assignor to Westinghouse Electric Corporation, East Pittsburgh, Pa., a corporation of Pennsylvania

Application June 1, 1948, Serial No. 30,473

3 Claims. (Cl. 175—30)

1

The present invention relates to lightning arresters, and more particularly, to a high-voltage lightning arrester unit of greatly reduced height, as compared to the height of lightning arrester units of conventional construction and equivalent voltage rating.

The lightning arrester unit of the present invention is especially adapted for use in high-voltage, station-type lightning arresters of unit construction, although it is a complete lightning arrester in itself and may be used as such. High-voltage, station-type lightning arresters are usually of unit construction, and are made up of a suitable number of lightning arrester units, of standard voltage ratings, each of the units consisting of a number of spark gap devices and valve elements, or valve-type resistors, assembled in series relation in a single stack and enclosed in a porcelain housing with metal end fittings. The individual arrester units are placed end-to-end in a vertical column, and the end fittings of adjacent units are bolted together for electrical and mechanical connection, so that all the units are connected in series. This type of construction results in a vertical column of great height as compared to its diameter, and in the higher voltage ratings, the height of the column is so great that it is not self-supporting, but must be supported from some suitable fixed support, such as a part of a substation structure, either by bracing or by suspension mounting. In the case of very high-voltage lightning arresters, the arrester column is so high that the required supporting structure and bracing become quite large and elaborate and are relatively expensive, thus adding considerably to the cost of the installation. The necessity of supporting the arrester in this way is, therefore, undesirable, but cannot be avoided with high-voltage lightning arresters of conventional construction, because of the necessarily great height of the arrester column.

Another problem in the design of high-voltage lightning arresters of conventional construction is that of obtaining sufficiently uniform voltage distribution across the tall column of arrester units. The arrester column is connected between a transmission line conductor and ground, so that it is subjected to the line-to-ground voltage, but because of the height of the arrester, the voltage does not divide uniformly between the individual arrester units. Satisfactory operation, however, requires a fairly uniform distribution of the voltage, and this has usually been obtained by the use of grading rings, which affect the electrostatic field surrounding the arrester, and provide suffi-

2

cient capacitance to make the voltage distribution sufficiently uniform for satisfactory operation. As the height of the arrester column is increased, however, it becomes increasingly difficult to obtain satisfactory voltage distribution in this way, and in very high-voltage lightning arresters, it is frequently necessary to employ two, or even three, grading rings, which are of very large diameter and thus undesirably increase the space required for the arrester and the necessary clearance distances to other nearby apparatus.

A lightning arrester construction which substantially eliminates, or at least greatly simplifies, the problems of supporting the arrester and of obtaining satisfactory voltage distribution is disclosed and claimed in a copending application of J. S. Ferguson, Serial No. 709,599, filed November 13, 1946, and assigned to Westinghouse Electric Corporation, now abandoned. In this 15 arrester unit, the height is materially reduced by placing the spark gap devices and valve elements in three columns, arranged side by side in a housing, with the gap devices in one column, and the valve elements in the other two, the three 20 columns being connected together in series within the housing. This construction permits a material reduction in the height of the arrester unit, for a given voltage rating, so that a vertical column of these units is relatively short and can be made self-supporting, even for very high voltage ratings. It has been found, however, that although this construction represents a material improvement in high-voltage lightning arresters, the arrangement of gap devices and valve elements in separate, series-connected columns disposed side-by-side in the housing results in considerable distortion of the electrostatic field surrounding the arrester elements, which adversely affects the breakdown voltage of the arrester unit, 25 both on surge voltages and on normal-frequency voltage.

The principal object of the present invention is to provide a lightning arrester unit for use in high-voltage, station-type arresters which is of 30 greatly reduced height, as compared to the height of lightning arrester units of conventional construction and equivalent voltage rating, and in which substantially uniform distribution of the voltage across the elements of the arrester unit 35 is obtained.

Another object of the invention is to provide a lightning arrester unit for high-voltage lightning arresters in which a plurality of gap devices and a plurality of valve elements are arranged in a 40 plurality of vertical columns in a housing, with

the gap devices distributed throughout the assembly, and with all the gap devices and valve elements connected together in a series circuit which extends back and forth between the columns, the arrangement being such that substantially uniform voltage distribution is obtained.

A further object of the invention is to provide a lightning arrester unit for high-voltage lightning arresters in which a plurality of spark gap devices and a plurality of valve elements are arranged in a plurality of vertical columns in a housing and connected together in series, and in which the gap devices are shunted by substantial capacitances in order to improve the voltage distribution.

A more specific object of the invention is to provide a lightning arrester unit for high-voltage lightning arresters in which a plurality of spark gap devices and a plurality of valve elements are arranged in a plurality of vertical columns in a housing, with the gap devices distributed throughout the assembly, and with insulating members interposed in the columns which, in effect, divide the columns into sections and which include conducting means for connecting the sections of different columns in series, the insulating members being so constructed and arranged that they provide substantial capacitances in shunt with the spark gap devices, so that good voltage distribution is obtained.

The invention will be more fully understood from the following detailed description, taken in connection with the accompanying drawing, in which:

Figure 1 is a vertical sectional view of a lightning arrester unit embodying the invention, the arrester elements themselves being shown in elevation;

Fig. 2 is a top plan view of the arrester unit with the top fitting and top plate removed;

Fig. 3 is a somewhat diagrammatic developed view showing the elements of the arrester in assembled relation; and

Fig. 4 is a schematic diagram showing the equivalent electrical circuit of the arrester unit.

The lightning arrester unit of the present invention is especially adapted for use in high-voltage, station-type lightning arresters of unit construction, although it will be apparent that it is a complete lightning arrester in itself and may be used alone. As shown in the drawing, the arrester unit has a porcelain housing 1, which is closed at the top by a metal top plate 2, a gasket 3 being interposed between the top of the housing 1 and the top plate 2. A flanged metal top fitting or casting 4, which has a substantially flat upper surface, is placed over the top of the housing 1 and secured to the housing by cementing, as indicated at 5, or by any other suitable means. The top fitting 4 is provided with a plurality of peripheral openings 6 for the reception of mounting bolts. An annular metal bottom fitting or casting 7, which has a flat bottom surface and peripheral bolt holes, is provided at the bottom of the housing 1 and secured to the housing by cementing, as indicated at 8, or by any other suitable means. The bottom of the housing 1 is closed by a metal bottom plate 9, which is secured to the bottom fitting 7 by means of bolts 10, a gasket 11 being interposed between the bottom plate 9 and the bottom of the housing 1 to seal the interior of the housing.

The arrester includes a plurality of spark gap assemblies 12 and a plurality of valve blocks, or valve-type resistors, 13. The spark gap assem-

blies 12 may be of any suitable construction and are shown as enclosed multiple-gap assemblies. Thus, each of the spark gap assemblies 12 is contained in a tube 14 of porcelain, or other insulating material, which is closed at the ends by metal end caps 15 secured to the tube 14 by soldering to a metallic glaze on the porcelain, or in any other suitable manner. The spark gap assemblies themselves consist of a plurality of metal electrodes 16 disposed in the tube 14 and spaced apart by insulating, or high resistance, spacers 17. A spring 18 is placed between the uppermost electrode 16 and the upper end cap 15 to retain the assembly of spark gaps firmly in position, and to obtain positive electrical contact with the two end caps 15.

The valve blocks 13 may be made of any suitable resistance material having valve characteristics, that is, a material which is normally semi-conducting, or of very high resistance, so that it will pass only a very small leakage current, but which sharply reduces its resistance under an excess-voltage surge to permit the discharge of high surge currents, and which rapidly increases its resistance after passage of the surge to reduce the current to a small value which a series gap can easily interrupt. The valve blocks 13 may, for example, be made of granular silicon carbide molded to the desired size and shape with a suitable binder, such as sodium silicate, and baked. A metal contact coating is preferably provided on the end surfaces of the valve blocks.

The spark gap assemblies 12 and valve blocks 13 are disposed in three vertical columns, which are equally spaced from each other within the housing and supported on the bottom plate 9. As seen in the developed view of Fig. 3, the left-hand column and right-hand column include both spark gap devices 12 and valve blocks 13, alternating with each other, while the center column contains only valve blocks 13.

The arrester also includes a number of elongated, generally cup-shaped insulating members 19, 20, 21, 22, 23 and 24. These insulating members are all of similar construction and may be made of a ceramic material, such as porcelain, or of any other suitable insulating material, preferably of high dielectric constant. Each of the insulating members has a base 25 and vertically extending side walls 26, which extend a substantial distance above the base 25 so that the insulating members are generally cup-shaped. The insulating members are made long enough to extend between two of the columns of arrester elements, as clearly shown in Fig. 3, and they are made wide enough to accommodate the spark gap devices 12 and valve blocks 13, which are of about the same diameter. Each of the insulating members also has a metallic coating 27 on its inside horizontal surface and a similar coating 28 on its outside horizontal surface. The thickness of these coatings is somewhat exaggerated in the drawing, for the purpose of illustration, but they should be made thick enough to be capable of carrying high discharge currents in the operation of the arrester.

The insulating members 19 through 24 are interposed in the three columns of arrester elements so that, in effect, they divide the columns into insulated sections. Thus, in the particular embodiment shown, the outside columns, as seen in Fig. 3, are each divided into three sections, each of which includes a spark gap assembly 12 and a valve block 13, except the top section of the left-hand column, which consists only of a spark

gap assembly, and the bottom section of the right-hand column, which includes two valve blocks. The center column is divided into five sections of two valve blocks each. The arrester elements of each section rest in one end of an insulating member and the elements of a section of another column are disposed in the opposite end of the insulating member, so that the insulating members extend between the columns, and their conducting coatings 27 and 28 provide electrical connection between the sections.

The conducting coatings 27 and 28 connect all the sections in a series circuit which extends back and forth between the columns. Referring to Fig. 3, the series circuit extends from the top plate 2 through the uppermost spark gap assembly 12 of the left-hand column, the upper conducting coating of the insulating member 29, the uppermost two valve blocks 13 of the center column, the lower conducting coating of the insulating member 19, a valve block and a spark gap assembly in the right-hand column, a conducting spacer 29, the upper conducting coating of the insulating member 21, two valve blocks in the center column, the lower conducting coating of the insulating member 20, a valve block and a spark gap assembly in the left-hand column, a conducting spacer 29, the upper conducting coating of the insulating member 22, two valve blocks 13 in the center column, and so on to the bottom plate 9. Thus the circuit extends circuitously from column to column to connect all the spark gap assemblies and valve blocks in series between the top plate 2 and the bottom plate 9. The conducting spacers 29 may be short sections of steel pipe, or they may be any other suitable conducting members of proper length and having sufficient rigidity and mechanical strength.

It will be noted that the insulating member 19 is inverted, with respect to the other insulating members, and that the metallic coating on its exterior surface is in electrical contact with the top plate 2. Similarly, the lowermost insulating member 24 is supported on conducting spacers 30, which may be similar to the spacers 29, but of greater length, and which support the left-hand and center columns and provide electrical connection between the lower metallic coating of insulating member 24 and the bottom plate 9. The thickness of the base 25 of the insulating members 19 to 24 is made great enough to space the adjacent arrester elements far enough apart to avoid any danger of puncture or flashover, since there may be a considerable difference of potential between the arrester elements on opposite sides of each insulating member. The side walls 26 of the insulating members extend vertically far enough to provide insulating barriers between parts of adjacent columns which may have a considerable potential difference between them during a discharge, and thus all possibility of flashover between different parts of the assembly is substantially eliminated.

Fig. 4 shows the equivalent electrical circuit of the arrester unit with all the elements of the arrester connected in series. The insulating members 19 through 24, with their conducting coatings 27 and 28 on opposite sides, inherently have relatively high capacitance, and the arrangement of these insulating members in the assembly, as described in detail above, is such that the capacitance of one of the insulating members is connected across each of the spark gap assemblies, since the conducting coating on one side of each

of the insulating members is connected on one side of a spark gap assembly and the conducting coating on the other side is connected in the circuit on the opposite side of the same spark gap assembly. Thus, the insulating members are represented as capacitors in Fig. 4, and it will be apparent from this figure that each spark gap assembly 12 is shunted by a substantial capacitance. The arrangement of the arrester elements, with the spark gap assemblies distributed throughout the series circuit, and with the capacitances provided by the insulating members across the spark gap assemblies, results in a very uniform distribution of voltage across the elements of the arrester unit, so that high and consistent values of breakdown voltage are obtained both on surge voltages and on the normal-frequency voltage.

In the use of the arrester unit described above in a high-voltage, station-type lightning arrester, a suitable number of these units are disposed end-to-end in a vertical column with their adjacent top and bottom fittings 4 and 7 bolted together for electrical and mechanical connection, to connect all the units in series. The arrangement of the arrester elements in each unit results in a unit of greatly reduced height and somewhat increased diameter, as compared to a conventional arrester unit of equivalent voltage rating, in which the same number of spark gap assemblies and valve blocks would be disposed in a single vertical stack. A vertical column of the new arrester units, therefore, is materially shorter in height than a lightning arrester of the same voltage rating built up of conventional arrester units, and the reduction in height is sufficiently great so that a vertical column of the new units, even for very high voltage ratings, is short enough to be self-supporting, eliminating the necessity for elaborate and expensive supporting and bracing structures. Such a column of arrester units is also short enough so that satisfactory voltage distribution across the arrester can usually be obtained without the use of grading rings, while the arrangement of the arrester elements within each unit described above results in uniform voltage distribution in each unit, so that high and consistent breakdown voltages are obtained.

A particular embodiment of the invention has been shown and described for the purpose of illustration, but it will be apparent that various modifications and other embodiments are possible within the scope of the invention. It is to be understood, therefore, that the invention is not restricted to the particular structural arrangement shown, but in its broader aspects, it includes all equivalent embodiments and modifications which come within the scope of the appended claims.

60 I claim as my invention:

1. A lightning arrester comprising an insulating housing, a plurality of spark gap devices and a plurality of valve-type resistors disposed in a plurality of vertical columns in the housing, at least some of said columns including both spark gap devices and resistors alternating with each other, a plurality of elongated, generally cup-shaped insulating members interposed in said columns between the elements thereof, each of said insulating members extending from one column to another column and having continuous conducting coatings on both surfaces in electrical contact with the adjacent elements of both columns, successive insulating members extending 65 between different pairs of columns in rotation to

connect all the gap devices and resistors in a series circuit extending from column to column, and to connect the capacitance of each of the insulating members across one of the gap devices.

2. A lightning arrester comprising an insulating housing, a plurality of spark gap devices and a plurality of valve-type resistors disposed in three vertical columns in the housing, two of said columns including both spark gap devices and resistors alternating with each other and the third column including only resistors, a plurality of elongated, generally cup-shaped insulating members interposed in said columns between the elements thereof, each of said insulating members extending from one column to another column and having continuous conducting coatings on both surfaces in electrical contact with the adjacent elements of both columns, successive insulating members extending between said third column and the other two columns alternately to connect all the gap devices and resistors in a series circuit extending from column to column and to connect the capacitance of each of the insulating members across one of the gap devices.

3. A lightning arrester comprising an insulating housing, a plurality of spark gap devices and a plurality of valve-type resistors disposed in three vertical columns in the housing, two of said columns including both spark gap devices
